CAM LAPING MACHINE

Herbert S. Indge, Westboro, and John C. Baker,
Worcester, Mass., assignors to Norton Company,
Worcester, Mass., a corporation of Massachusetts

Application April 1, 1941, Serial No. 386,356

12 Claims. (Cl. 51—151)

The invention relates to lapping machines, and more particularly to a cam lapping machine.

One object of the invention is to provide a simple and thoroughly practical cam lapping machine. Another object of the invention is to provide a multiple spindle cam lapping machine, whereby a plurality of cams may be simultaneously lapped. Another object of the invention is to provide a cam lapping machine, in which a flexible abrasive element, such as abrasive cloth or paper, is rocked toward and from the work axis in a controlled movement to lap the periphery of the cam to the desired finish.

A further object of the invention is to provide an automatically operated cam lapping machine, in which the lapping operation may be continued for a predetermined time interval. A further object of the invention is to provide an automatic cam lapping machine which is arranged so that after the lapping operation has proceeded for a predetermined time interval, the lapping element will be automatically removed from the work, the work rotation will be stopped, and the reciprocation of the work spindle also stopped and the work piece automatically ejected from the machine. Other objects will be in part obvious or in part pointed out hereinafter.

The invention accordingly consists in the features of construction, combinations of elements, and arrangements of parts, as will be exemplified in the structure to be hereinafter described, and the scope of the application of which will be indicated in the following claims.

In the accompanying drawings, in which is shown one of various possible embodiments of the mechanical features of this invention,

Fig. 1 is a front elevation of the improved multiple spindle cam lapping machine;

Fig. 2 is a combined hydraulic piping and electrical wiring diagram;

Fig. 3 is a front elevation, on an enlarged scale, of one of the cam lapping heads;

Fig. 4 is a side elevation, on an enlarged scale, of one of the cam lapping heads;

Fig. 5 is a vertical sectional view, on an enlarged scale, taken approximately on the line 5—5 of Fig. 3, through one of the cam lapping heads;

Fig. 6 is a fragmentary rear elevation, on an enlarged scale, of one of the cam lapping heads, having parts broken away and shown in section;

Fig. 7 is a horizontal sectional view, on an enlarged scale, taken approximately on the line 7—7 of Fig. 5;

Fig. 8 is a fragmentary front elevation of the

abrasive lapping element supporting, guiding and feeding mechanism;

Fig. 9 is a fragmentary side elevation of the mechanism as shown in Fig. 8;

Fig. 10 is a fragmentary detail view of the limit switch actuating mechanism;

Fig. 11 is a fragmentary sectional view, on an enlarged scale, showing the limit switch actuating mechanism;

Fig. 12 is a perspective view, on an enlarged scale, of the work piece;

Fig. 13 is a fragmentary detail view, on an enlarged scale, of the work piece, work arbor and spindle, partly in section; and

Fig. 14 is a fragmentary plan view of the guiding mechanism for the work ejector.

The improved cam lapping machine, as shown in Fig. 1, is a multiple head lapping machine, whereby four work heads may be simultaneously operated simultaneously to lap a plurality of cams. The heads 21 are identical in construction, consequently only one of the heads has been shown and described in detail. The lapping head 21, that is, the left-hand head (Fig. 1) has been shown in detail in the drawings. The remaining lapping heads 21a, 21b and 21c have been illustrated only in Fig. 1 and in the diagrammatic showing in Fig. 2. Corresponding parts of the heads 21a, 21b and 21c have been designated where shown by the corresponding reference numeral applied to the lapping head 21 suffixed with the letters a, b and c.

The lapping head 21 is provided with a rotatable spindle 22 (Fig. 5) which is rotatably journalled in spaced anti-friction bearings 23 and 24. A multi-V-groove pulley 25 is connected to rotate the spindle 22. A motor driving mechanism is provided therefor comprising an electric motor

26 mounted on the upper surface of the head 21. A motor shaft 27 is provided with a multi-V-groove pulley 28 which is connected by a multiple V-belt 29 with the pulley 25 to transmit a rotary motion to the spindle 22. The spindle 22 is a hollow spindle provided with a clearance aperture 30 within which is supported a work supporting spindle 31. The work spindle 31 is journalled in sleeve bearings 32 and 33 and arranged so that it may be rotated with the hollow spindle 22 and at the same time reciprocated axially during said rotary motion during a lapping operation. The spindle 31 is slidably keyed to a bushing 34 which is in turn fixedly mounted relative to the pulley 28.

A master cam 35 is keyed to a hub 36 which is fixedly mounted to rotate with the pulley 25 and

work spindle 31 (Fig. 5). The master cam 35 serves to control the movement of the lapping element to be hereinafter described. It is desirable to provide means for rotarily adjusting the position of the master cam 35 relative to the spindle 31 and the spindle 22 in order that a work piece 48 supported by the spindle 31 may be positioned in timed relationship with the master cam 35. The hub 36 supporting the master cam 35 is formed as an integral part of a flanged member 37 which is fixedly connected by screws 38 to support the pulley 25. The hollow spindle 22 is provided with an integral flange 39 which has a central aperture 40 to support a hub 41 formed integral with the flange 37 and the hub 36. A plurality of screws 42 serve to hold the flange 37 in adjusted position relative to the flange 39, only one of these screws being illustrated in Fig. 5. The screw 42 passes through an elongated arcuate slot 43 formed in the flange 37 and is screw threaded into the flange 39 so that the parts may be rotarily adjusted to time the cam 35 relative to the located work piece 48 in setting up the machine.

In order to facilitate rotarily adjusting the master cam 35, a gear segment 44 is cut upon a portion of the periphery of the flange 39. When it is desired to time the cam 35, a pinion having a manually operable handle may be inserted in an aperture 45 into mesh with the gear segment 44. The screws 42 may then be loosened and the pinion meshing with the gear segment 44 rotated to rotarily adjust the flange 37 relative to the flange 39 to facilitate accurate timing of the master cam 35. After the desired adjustment has been made, the clamping screws 42 may again be clamped to lock the flange 37 to the flange 39, after which no further adjustment is required unless it is desired to change the master cam and to set up the machine for a different lapping operation.

A work supporting adapter 46 is screw threaded onto the front end of the spindle 31 (Figs. 5 and 13). The adapter 46 is provided with a cylindrically shaped work supporting arbor 47 which serves as a support for a work piece 48 having a cam face 49 to be lapped. The adapter 46 is provided with a work locating and driving key 50 which engages a slot cut in the end of the work piece 48 and serves to locate successive work pieces so that the cam 49 is accurately located in timed relationship with the master cam 35.

The arbor 47 serves as a rotatable support for the work piece 48 while the cam 49 is lapped to the desired and predetermined extent. It is desirable to provide a support for the outer end of the work piece to steady it against the thrust of a lapping element to be hereinafter described. A rotatable spring-pressed footstock center 54 is carried by a pivotally mounted footstock 55. The footstock center 44 is arranged to engage a central aperture on the outer end of the work piece 49. In order to facilitate loading and unloading of the machine, the footstock 55 is supported on a vertically extending rock shaft 56 so that it may be swung in a clockwise direction (Fig. 7) to an inoperative position during unloading and loading of work pieces.

The shaft 56 is arranged to be rocked automatically in timed relation with the other mechanisms of the machine such as, for example, by means of a hydraulically operated mechanism comprising a hydraulic cylinder 57 which contains a slidably mounted piston 58. The piston rod 59 carries a head 60 at its left-hand end

(Fig. 7). The head 60 is provided with an elongated slot 61. A pivotally mounted plate 62 is supported on a rock shaft 63 on the lapping head 21. The plate 62 is provided with a stud 64 which 5 rotatably supports a roller 65 which in turn rides in the elongated slot 61 in the head 60. The lower end of the rock shaft 56 is provided with an arm 66 having an elongated slot 67. The plate 62 carries a stud 68 which rides within the elongated slot 67. These parts have been illustrated 10 in Fig. 7 in an operative position, in which a work piece 48 has just been lapped to the predetermined extent, and the parts are just about to move into an unloading position.

Fluid under pressure has just been admitted to a cylinder chamber 69 to cause the piston 58 and piston rod 59 to move toward the left (Fig. 7). The movement of the piston rod 59 together with the head 60 and elongated slot 61 toward the left 20 serves to rock the plate 62 in a counterclockwise direction (Fig. 7) about the axis of the rock shaft or stud 63. This movement of the plate 62 causes the stud 68 to ride toward the left within the elongated slot 67 which serves to rock the arm 66, the rock shaft 56, and the footstock 55 together with the work supporting stud or center 54 in a clockwise direction to an inoperative position with the work center 54 out of engagement with the work piece 48. During this movement of the parts, fluid within a cylinder chamber 70 is exhausted in a manner to be hereinafter described into a reservoir 71 contained within the base of the machine.

A fluid pressure system is provided for conveying fluid under pressure to the cylinders 57, 57a, 57b and 57c and also to other parts of the machine, as will be hereinafter described. The fluid reservoir 71 is supported within the base 20 of the machine. A motor driven fluid pump 72 draws fluid from the reservoir 71, through a pipe 73, and forces fluid under pressure through a pipe 74 to control valves 75, 75a, 75b and 75c on heads 21, 21a, 21b and 21c, respectively, which serve to control the admission of fluid to the cylinders 57, 57a, 57b and 57c. A variable pressure relief valve 76 is provided in the pipe line 74 by means of which excess fluid under pressure in the system may be returned through a pipe 77 into the reservoir 71.

The control valve 75 is a piston type control valve comprising a valve stem 78 having formed integrally therewith valve pistons 79, 80, 81 and 82 (Fig. 7). The control valve is hollow, being provided with an axially extending bore 83. In the position of the parts as shown in Fig. 7, fluid under pressure from the pipe 74 enters a valve chamber located between the valve pistons 80 and 81 and passes through a passage 84 into the cylinder chamber 69 to move the piston 58 toward the left (Fig. 7). As previously stated, the parts as shown in Fig. 7 are just as a work piece has been lapped to the predetermined extent and the control valve 75 has been shifted into its right-hand end position by means of a compression spring 85. During the movement of the piston 58 toward the left (Fig. 7), fluid within the cylinder chamber 70 passes out through a passage 86 into a valve chamber located between the valve pistons 79 and 80 and passes through the central aperture or bore 83 within the valve 75 and out through a pipe 87 which exhausts into the reservoir 71. Fluid under pressure exhausting from the cylinders 57a, 57b and 57c passes through pipes 87a, 87b and 87c into the reservoir 71. The compression spring 85 surrounds the valve stem

78 and is interposed between a bracket 88 fixed on the lapping head 21 and a collar 89 which is fixedly mounted on the valve stem 78. The spring 85 normally serves to hold the valve 75 in its right-hand end position, as shown in Fig. 7.

A manually operable control lever 90 is pivotally mounted on a stud 91 fixedly mounted on the head 21 (Fig. 4). A downwardly extending portion of the lever 90 is connected by a stud 92 with one end of a link 93. The other end of the link 93 is connected by a stud 94 with a rock arm 95 which is mounted on the outer end of a rock shaft 96. The rock shaft 96 is journaled in a bearing 97 formed integral with the lapping head frame 21. A rock arm 98 is fixedly mounted on the inner end of the rock shaft 96. The arm 98 supports a stud 99 which rides in a groove 100 formed in a spool-shaped member 101 which is fixedly mounted on the outer end of the valve stem 78. When it is desired to start a lapping cycle, the lever 90 is shifted in a clockwise direction (Fig. 4) to move the link 93 toward the left (Fig. 4) so as to rock the arm 95, the rock shaft 96, and the rock arm 98 in a counterclockwise direction and, through the stud 99 and spool-shaped member 101, serves to move the valve stem 78 toward the left (Fig. 7). This movement of the valve stem 78 shifts the valve 75 into its reverse position so that fluid under pressure from the pipe 74 entering the valve chamber located between the valve pistons 80 and 81 passes through the passage 86 into the cylinder chamber 70 to move the piston 58 toward the right (Fig. 7).

It is desirable to hold the valve 75 in its left-hand end position (Fig. 7) during a lapping operation. A pivotally mounted latch 102 supported by a stud 103 is actuated by means of a solenoid 104. When the valve stem 78 is moved into a left-hand end position and the solenoid 104 is energized, the latch 102 latches against the collar 103 which is fixedly supported on the valve stem 78. The latch 102 maintains the valve in its left-hand end position while the solenoid 104 remains energized.

Due to the shape of the work piece 48, namely, a work piece having oppositely extending arms normal to its axis adjacent to one end thereof, an ejector mechanism is provided comprising a cup-shaped ejector 110 which is provided with diametrically opposed outwardly extending studs 111 and 112. A yoke-shaped arm 113 is fixedly mounted on the upper end of a rock shaft 114. The opposed arms of the yoke 113 are each provided with elongated slots 115 (Fig. 7), only one of which has been clearly shown in the drawings. The oppositely extending studs 111 and 112 carried by the ejector 110 are arranged to slide in the elongated slots 115. It will be readily apparent from the foregoing disclosure that if the rock shaft 114 is rocked in a counterclockwise direction (Fig. 7), the arm 113 will rock also in a clockwise direction and due to the elongated slots 115, the ejector together with the pins 111 and 112 may be moved in a straight line path automatically to withdraw the work piece 48 from the supporting arbor 47.

The ejector 110 is preferably moved in a substantially straight line path during the ejecting movement. A substantially U-shaped bracket 116 is fixedly mounted on the ejector member 110 (Figs. 5 and 14). A guide block 117 is fixedly mounted on the lapping head 21 and is provided with parallel guiding surfaces 118 and 119 (Fig. 14) which serve to guide the bracket 116 and the

ejector 110 in a straight line path as it is moved in either direction.

It is desirable that the ejector 110 be moved automatically to and from an operating position in timed relation with the other parts of the machine. This is preferably accomplished by means of a pair of toggle levers 120 and 121 which are connected at their adjacent ends by a stud 122 (Fig. 7). The toggle lever 121 is connected by a stud 123 with the plate 62. The toggle lever 120 is connected by a stud 124 to a rock arm 125 mounted on the lower end of the rock shaft 114. At the end of a lapping operation, when the plate 62 is rocked in a counterclockwise direction by movement of the piston 58 toward the left, a corresponding movement will be imparted through the stud 123, toggle levers 121 and 120, to rock the arm 125, the rock shaft 114, yoke member 113, in a counterclockwise direction to move the ejector member 110 rapidly toward the left so as to withdraw a finish lapped work piece 48 from position on the arbor 47. During the ejecting movement, the toggle levers 120 and 121 move together until a projecting boss 126 on the lever 120 engages a stop screw 127 on the head 21 after which continued movement of the plate 62 serves to break the toggle levers 120 and 121 from their straight line path of movement during the remainder of the swinging movement of the plate 62. A flat type spring 128 carried by the plate 62 normally tends to urge the toggle levers 120 and 121 into a straight line position.

Similarly, at the start of a lapping operation 35 when the control lever 90 is shifted and the piston 58 moves toward the right (Fig. 7), the movement of the plate 62 in a clockwise direction about its supporting pivot stud 63 serves through the stud 123, toggle levers 121 and 120, 40 and stud 124, to rock the arm 125, the shaft 114, and yoke 113 in a clockwise direction, which movement serves through the studs 111 and 112 to move the ejector member 110 into an operative position, after which the work piece may be 45 inserted on the arbor before the housing 55 is swung into an operative position with the yieldably mounted spindle 54 in supporting engagement with the outer portion of the work piece 48.

Work reciprocation

A reciprocating mechanism is provided for imparting a rapid reciprocating movement to the work piece 48 during the lapping operation. The rear end of the work spindle 31 supports a sleeve 133 which in turn supports an anti-friction bearing 134. A hydraulic reciprocating mechanism is provided comprising a self-contained fluid motor 135 having a cylinder 136 having a slidably mounted piston 137 therein. The piston 137 is connected to one end of a piston rod 138, the other end of which is supported by the anti-friction bearings 134. A control valve is formed as an integral part of the motor 135. The motor 135 has not been illustrated in detail, since this motor is identical with that shown in the prior U. S. patent to Wallace H. Wood, No. 2,212,871, dated August 27, 1940, to which reference may be had for details of disclosure not contained herein. The motor 135 contains a slidably mounted piston type pilot valve 139. The pilot valve 139 is hollow, being formed with a central axially extending cylindrical aperture which supports a slidably mounted shuttle-type reversing valve 140. The pilot valve 139 is provided with a valve stem 70 75 141 which projects from the motor casing and

is provided at its outer end with a pair of adjustable reversing dogs 142 and 143. A bracket 144 is fixedly mounted on the motor 135. A pivotally mounted reversing lever 145 is connected by means of a stud 146 with the bracket 144. The reversing lever 145 projects downwardly and is provided at its lower end with a spherical shaped end portion 147 which is arranged in the path of the pilot valve dogs 142 and 143. The reversing lever 145 is connected by means of a stud 148 with the piston rod 138.

The endwise movement of the piston rod 138 serves to rock the reversing lever 145. When the spherical end 147 of the lever 145 engages either the dog 142 or the dog 143, depending on the direction of movement of the piston 137, continued movement shifts the valve stem 141 to change the position of the pilot valve 139 which operates through the reversing valve 140 to reverse the direction of flow of fluid to the cylinder 136. The operation of the fluid motor 135 is fully disclosed and described in the prior patent to Wood, No. 2,212,871, to which reference may be had for details of operation not contained herein.

The starting and stopping of the fluid motor 135 for reciprocating the work spindle 31 is preferably controlled automatically in timed relation with the other mechanisms of the machine. In the preferred form, a normally closed piston type valve 150 is mounted on the end of the cylinder 57 (Fig. 2). The movable valve member 151 is normally held in a closed position by means of a compression spring 152. A valve actuating rod 153 is operatively connected to the piston rod 59 so that when fluid under pressure is admitted to move the piston 58, the valve member 151 will be opened or closed so as to admit fluid to the motor 135 or to cut off fluid under pressure therefrom. Fluid under pressure from the pipe 74 passes through a pipe 154 into a valve chamber 155. In the position shown in Fig. 2, fluid under pressure entering the chamber 155 passes outwardly through a pipe 156 to the fluid motor 135. Fluid exhausting from the motor 135 is exhausted directly through a pipe 157 into the reservoir 71.

As the piston 58 moves toward the left, the piston rod 59 being connected to the valve stem 153 causes the valve member 151 to move toward the left aided by the compression of the spring 152 to close the valve, thus preventing passage of fluid from the valve chamber 155 into the pipe 156, thus cutting off fluid under pressure from the work reciprocating motor 135 automatically after the lapping operation has been completed to stop reciprocation of the spindle 31 and work piece 48.

In order to lap the cam 49 to the desired finish, it is essential to provide a lapping element which is movable relatively toward and from the work axis in order that the desired contour may be maintained on the cam 49 during the lapping operation. In the preferred form, a lapping element 160 is mounted on one end of a rock shaft 161. The rock shaft 161 is rotatably journaled in bearings 162 and 163 which are formed integral with or fixedly mounted on the lapping head 21. A rock arm 164 is fixedly mounted on the rear end of the rock shaft 161. A stud 165 mounted at the upper end of the rock arm 164 serves as a support for a rotatable master cam follower roller 166. The master cam follower roller 166 is normally maintained in operative engagement with the periphery of the master cam 35 by means of a tension spring 167. The

spring 167 is fastened at one end to a hook 168 fixedly mounted on or adjacent to the upper end of the rock arm 164 and the other end of the spring is fixedly mounted on a stud (not shown) which is fixed relative to the head 21. It will be readily apparent from the foregoing disclosure that when the work spindle 31 is rotated during a lapping operation, the master cam 35 rotated thereby will impart a controlled oscillating movement to the lapping head 160 so as to maintain the lapping element in uniform operative lapping engagement with the cam 49 during a lapping operation.

Lapping element

The lapping element 160 (Figs. 4, 8 and 9) comprises an arm 170 which is fixedly mounted on the rock shaft 161. The arm 170 supports a pair of spaced side plates 171 and 172 (Fig. 4) which in turn support a lapping head 173. The lapping head 173 is provided with a yieldably mounted nose piece 174. The head 173 and the nose piece 174 are covered by a piece of flexible yieldable friction material 175 which serves as a support for a strip of abrasive paper or cloth 176. The spring-pressed nose piece 174 is preferably adjusted so that when the master cam roller 166 is riding in engagement with the master cam 35, the nose piece 174 will be under compression to maintain the strip of abrasive paper 176 in uniform lapping engagement with the periphery of the cam being lapped.

In the preferred form a continuous roll of abrasive paper 177 is mounted on a spindle 178 and is supported by side flanges 179 and 180 (Fig. 4). The strip of abrasive paper 176 passes from the roll 177 over an idler roller 181 and passes downwardly between an idler roller 182 and around the lapping head 173 and nose piece 174 (Figs. 3, 4, 8 and 9). The abrasive paper 176 then wraps around an idler roller 183 and passes to a paper feeding mechanism.

An abrasive paper indexing or feeding mechanism is provided automatically to advance the abrasive paper 176 a predetermined distance after each lapping operation has been completed to present a fresh portion of abrasive paper 176 around the nose piece 174 for the next lapping operation. By utilizing a fresh portion of abrasive paper for each operation, a uniform lapping or abrading operation may be accomplished in a predetermined time. The feeding mechanism may comprise a pair of corrugated or rough surfaced feed rollers 185 and 186. The roller 185 is rotatably supported on the rock shaft 161. The roller 186 is rotatably supported on a stud 187 which is carried by a pivotally mounted frame 188. The frame 188 is pivotally supported on a stud 189 which is in turn supported by the rock arm 170. A compression spring 190 interposed between the upper end of the frame 188 and a projection lug 191 of the rock arm 170 serves to exert a pressure yieldingly to urge the roller 186 toward the roller 185.

The abrasive paper 176, after leaving the nose portion of the head 173, wraps around the idler roller 183 (Fig. 8) and around the left-hand side face of the rock arm 170 and around the feed roller 185, passes between the feed rollers 185 and 186, and then passes upwardly over an idler roller 192 and is coiled up in a coil 193 located between a plate 194 and the plate 179. The slack on the return side of the worn abrasive paper is taken up by manual rotation of the disk 194.

A pair of involute gears 195 and 196 are rotat-

ably mounted respectively on the shaft 61 and stud 187. The gear 195 is fixedly mounted to rotate with the roller 185 and the gear 196 is fixedly mounted to rotate with the roller 186 so that both of the feed rollers 185 and 186 may be synchronously and positively rotated to produce the desired indexing movement.

A ratchet wheel 197 is mounted on the stud 187 and is fixedly mounted to rotate the gear 196 and the feed roller 186. An index or feed pawl 198 is pivotally supported on a stud 199 and is arranged to remain in operative contact with the teeth of the ratchet wheel 197 by the influence of gravity. The stud 199 is mounted on one end of a rock arm 200 which is pivotally supported by a stud 201 on the lapping head 21. An arm 202 formed integral with the arm 200 extends in the opposite direction therefrom. A roller 203 is rotatably supported at the outer end of the arm 202 and is arranged in the path of a cam 204. The cam 204 is formed on the outer portion of a quadrant shaped arm 205 which is fixedly mounted to swing with the rock shaft 56 and the housing 55.

When the footstock 55 is rocked to an inoperative position to move the center 54 out of engagement with the work to facilitate removal of the finish lapped work piece, the cam 204 swings in a clockwise direction (Fig. 7), which movement swings the cam 204 into engagement with the roller 203 (Fig. 3) after which continued movement serves to rock the lever 202—200 in a clockwise direction (Fig. 3) to cause a downward movement of the feed pawl 198, which movement causes a clockwise indexing movement of the ratchet wheel 197 (Figs. 3 and 8), gear 196 and feed wheel 186 and at the same time, through the gear 196, rotates the gear 195 and the feed roller 185 in a counterclockwise direction to advance the abrasive paper 176, that is, to pull a predetermined amount of the worn abrasive around the nose piece 174, thus presenting a fresh abrading surface for the next lapping operation. The worn abrasive paper feeds downwardly in the direction of an arrow located under the reference numeral 170, consequently the thrust on the abrasive paper 176 is downwardly. The work piece rotates in a counterclockwise direction (Fig. 8) so that the thrust of the rotating work piece 48 is against the positively geared feeding rolls 185 and 186, thus preventing any direct pull or thrust on the new abrasive paper from the roll 177 during the lapping operation.

The pawl 198 is adjustably supported in an arm 198e to facilitate adjustment thereof. The arm 198e is provided with a slot having a groove in its side face to support the pawl 198. A pair of binder or clamping screws 198f and 198g are provided to clamp the pawl 198 in adjusted position. If the effective length of the pawl 198 is decreased or shortened, the arms 200—202 will be maintained in a slightly advanced position in a clockwise direction under the influence of gravity so that the roller 203 will not be engaged by the cam 204 as quickly during the swinging movement of the cam 204. By adjusting the position of the pawl 198 relative to its supporting arm 198e, the parts may be adjusted so that after each lapping operation one or more teeth of the ratchet wheel 197 may be picked up after each lapping operation has been completed to advance or index the abrasive paper 176 by the desired and predetermined amount.

A mechanism may be provided automatically

to separate the lapping element from the work piece and the master cam follower roller 166 from the master cam 35 after a lapping operation has been completed in order to facilitate removal of the lapped work piece. This mechanism is preferably a hydraulically operated mechanism comprising a fluid pressure cylinder 210 which is pivotally supported by means of a stud 211 on the lapping head 21. A piston 212 is slidably mounted within the cylinder 210 and is connected to one end of a piston rod 213. The other end of the piston rod 213 is connected by means of a stud 214 with the rock arm 164 which supports the follower roller 166. A fluid pipe 215 is connected between the control valve 75 and the cylinder 210 so that when the valve 75 is in the position as shown in Figs. 2 and 7, fluid under pressure passing through the pipe 74 into a valve chamber located between the valve pistons 80 and 81 will pass not only to the cylinder 57 but will also pass through the pipe 215 into a cylinder chamber 217 to cause the piston 212 to move upwardly toward the left to rock the rock arm 164 in a counterclockwise direction so as to separate the master cam follower roller 166 from the master cam 35. The rocking movement of the arm 164 will be transmitted through the rock shaft 161 simultaneously to rock the lapping element away from operative engagement with the work piece. A cylinder chamber located above the piston 212 is connected by a pipe 216 with the exhaust pipe 81, whereby any fluid which leaks by the piston 212 is free at all times to exhaust into the reservoir 71.

35. An electrical control mechanism is provided for each of the lapping heads automatically to control the duration and extent of the lapping operation. The electrical control apparatus consists of push button switches 220, 220a, 220b and 220c for rendering the lapping head circuit operative. Electrical time delay relays 221, 221a, 221b and 221c are provided which may be of any of the standard electrical relays commonly known in the machine tool control art such as, for example, that known as the "Microflex" manufactured by the Eagle Signal Corporation, of Moline, Illinois. Magnetic starter switches 222, 222a, 222b and 222c are provided for controlling the stopping and starting of the electric motors 26, 26a, 26b and 26c, respectively. Motor brake switches 223, 223a, 223b and 223c are provided for rapidly stopping the rotation of the motors 26, 26a, 26b and 26c, respectively, at the end of a lapping cycle. Normally open limit switches 224, 224a, 224b and 224c are arranged so that they may be automatically closed at the start of the lapping operation. The closing of the limit switches 224, 224a, 224b and 224c serves to set the time relays 221, 221a, 221b and 221c, respectively, in motion and simultaneously, through the magnetic starter switches 222, 222a, 222b and 222c, to start the rotation of the electric motors 26, 26a, 26b and 26c and at the same time to energize the solenoids 104, 104a, 104b and 104c to latch the control valves 75, 75a, 75b and 75c, respectively, in an operative position for a lapping operation. After the lapping operation proceeds for a predetermined time interval, as called for by the setting of the time relay 221, the relay 221 operates to open the circuit so as to deenergize the solenoid 104, thus releasing the latch 102 whereupon the released compression of the spring 85 shifts the control valve 75 into the position shown in Figs. 2 and 7.

70. The limit switch 224 is preferably actuated in

timed relation with the movement of the piston 58 so that when the control lever 90 is shifted to start a lapping cycle, the piston 58 moves toward the right (Fig. 7) to start a lapping operation. The piston rod 57 is provided with a collar 227 which supports a stud 228. A rock arm 229 serves as a support for a stud 230. The rock arm 229 is provided with a yoked portion adjacent to its other end which is connected by a pivot stud 231 with a rock shaft 232. The rock shaft 232 is rotatably journaled in bearings (not shown) within the lapping head 21. It will thus be seen that the rock arm 229 may be rocked in two directions, namely, about the axis of the shaft 232 as a pivot and also in a plane at right angles thereto about the stud 231 as a pivot. A rock arm 233 (Fig. 7) is fixedly mounted on the rock shaft 232. A pair of opposed balanced compression springs 234 and 235 normally tend to hold the rock arm 233 together with the rock shaft 232 and the rock arm 229 in the position shown in Figs. 7, 10 and 11. The rock arm 229 is provided with a projecting end portion 236 which is normally arranged in the path of an actuating plunger 237 of the limit switch 224.

From the foregoing disclosure it will be readily apparent that if the rock arm 229 is rocked in a counterclockwise direction (Fig. 14) about the axis of the rock shaft 232 as a pivot, the end portion 236 of the rock arm 229 will engage the plunger 237 to close the limit switch 224. It will also be apparent that if the rock arm 229 is moved about the axis of the stud 231 as a pivot, the end portion 236 will be moved laterally out of the path of the switch actuating plunger 237. The parts shown in Figs. 7 and 10 are shown as a work piece has been finish lapped and the lapping cycle is about to be terminated, fluid under pressure having just been admitted through the passage 84 into the cylinder chamber 69 (Fig. 7) to move the piston 58 and piston rod 59 toward the left (Figs. 7 and 10). Movement of the piston rod 59 toward the left moves the collar 227 also toward the left (Fig. 10) and continued movement thereof due to the cam faces of the studs 228 and 230, will swing the rock arm 229 in a counterclockwise direction about the axis of its supporting stud 231 as a pivot so that the end portion 236 thereof will be moved upwardly (Fig. 10) out of the path of the limit switch plunger 237. The collar 227 moves toward the left to the full line position 227a (Fig. 11) where it remains during the unloading and loading of a work piece.

After the machine has been loaded and it is desired to start a new lapping cycle, the manually operable lever 90 is shifted to move the control valve 75 into a starting position so as to admit fluid under pressure into the cylinder chamber 70 to move the piston 58 toward the right (Fig. 7), which movement shifts the piston rod 59 toward the right, moving the collar 227 from position 227a into the broken line position 227 (Fig. 14). During this movement of the collar 227 toward the right, a cam face on the stud 228 (on the collar 227) engages a cam face on the stud 230 (on the rock arm 229) (Fig. 14) which serves to rock the rock arm 229 in a counterclockwise direction (Figs. 7 and 14) about the axis of the rock shaft 232, which movement shifts the end portion 236 into engagement with the actuating plunger 237 of the limit switch 224 to close the limit switch 224 in a manner above described, serving to set the time relay 221 in motion, through the electric magnet starter switch 222,

to start the work drive motor 26 and at the same time energize the solenoid 104 to move the latch 102 upwardly to latch the valve 75 in an operative position. It will thus be seen that when the collar 227 moves in a direction toward the left after a lapping operation has been completed, the arm 229 is moved out of operative contact out of the path of the plunger 237 of the limit switch 224 and on the return stroke of the collar 227 at the start of the next lapping operation, the lever 229 is swung so that its operative end portion 236 engages and actuates the limit switch plunger 237 to close the normally open limit switch 224 to initiate the next lapping cycle. All 15 the lapping heads 21a, 21b and 21c operate in the same manner.

The operation of the improved cam lapping machine will be readily apparent from the foregoing disclosure. Assuming all of the parts and 20 mechanisms to have been previously adjusted, the operator closes the push button switches 220, 220a, 220b and 220c which render the machine circuits in condition for operation. A work piece 48 is then manually placed in position on the 25 work supporting arbor 47 with the driving key 50 engaging the notch formed in the right-hand end of the work piece (Fig. 13). The control lever 90 is then manually shifted in a clockwise direction (Fig. 4), which movement operates in 30 a manner above described to shift the control valve stem 78 toward the left (Fig. 7), which positions the valve 75 so that fluid under pressure from the pipe 74 is admitted to the cylinder chamber 70 to move the piston 58 toward the right into the position illustrated in Fig. 7.

During this movement of the piston 58, the 35 footstock 55 is shifted in a counterclockwise direction to the position illustrated in Fig. 7 with the work supporting spring pressed plunger 54 (Fig. 5) in operative supporting engagement with the work piece 48. Also during the movement of the piston 58 toward the right, the limit switch 224 will be closed in a manner above described and held closed for a brief period due to the 40 shape of the cam faces on the studs 228 and 230. The closing of the limit switch 224 serves to set the time relay 221 in motion, also through the magnetic starter switch 222 to start the motor 26 to rotate the work piece 48, and at the same 45 time to energize the solenoid 104 which lifts the latch 102 so as to hold the valve 75 in an operating position during the lapping operation. In this position of the valve 75, fluid within the cylinder chamber 217 (Fig. 6) exhausts through 50 the pipe 215 into a valve chamber located between the valve pistons 81 and 82 and out through the pipe 87 into the reservoir 71. The released tension of the spring 167 serves to facilitate this movement and rapidly to swing 55 the master cam follower roller 166 into operative engagement with the periphery of the master cam 35. This movement of the master cam follower roller 166 serves to rock the rock shaft 161 so as to move the lapping element 160 into 60 an operative position with the abrasive paper 174 in operative engagement with the periphery of the cam 49 to be lapped.

During movement of the piston 58 into its 65 right-hand end position at the start of a lapping operation, the valve 151 is opened so that fluid under pressure within the pipe 74 passes through the pipe 154, the valve chamber 155, and the pipe 156 to the fluid motor 135 to start reciprocation of the piston 137 which is transmitted to the 70 piston rod 138 to oscillate or reciprocate the

work supporting spindle 31 so that the cam 49 being lapped is reciprocated in an axial direction at a comparatively rapid rate during its rotation so that a highly finished surface is produced on the work piece by the lapping operation.

The lapping operation continues for a predetermined time interval as governed by the setting of the electric time delay relay 221. After the predetermined time interval has elapsed, the time relay 221 breaks a circuit to deenergize the solenoid 184, which movement serves to release the latch 102, thus releasing the compression of the spring 85 which moves the valve 75 rapidly toward the right into the position shown in Figs. 2 and 7. The initial movement of the valve 75 toward the right is retarded by means of a stop screw 240 (Fig. 9) which is engaged by a lug 241 formed on the inner surface of the link 93. The stop screw 240 and lug 241 hold the valve 75 in a central position so that fluid under pressure in the pipe 75 passing into the valve chamber located between the valve pistons 80 and 81 may pass only through pipe 215 into the cylinder chamber 217 (Fig. 6), which movement serves to separate the master cam follower roller 166 from the master cam 35 and at the same time serves to rock the arm 170 in a clockwise direction (Fig. 8) to move the abrasive lapping paper 176 out of operative engagement with the cam 49 being lapped.

During this swinging movement of the arm 170, the screw 240 is swung also in a clockwise direction (Fig. 8) out of the path of the stop lug 241, after which the compression of the spring 85 is again released to complete the movement of the valve stem 78 into its right-hand end position. After the valve 75 has reached its right-hand end position (Fig. 7), fluid under pressure is admitted into the cylinder chamber 69 to start the piston 58 moving toward the left. This movement serves in a manner above described to remove the footstock 55 and the work supporting spring-pressed plunger 54 to an inoperative position and at the same time serves through the toggle levers 120 and 121 rapidly to shift the work ejector member 110 toward the left (Fig. 7) to eject a finish lapped work piece 48 from the work supporting arbor 47, thus completing the lapping operation.

After the predetermined time interval, the time relay 221 not only breaks the circuit to deenergize the solenoid 184 but also, through the magnetic starter switch 222 and the motor break switch 223, instantaneously stops the rotation of the work supporting and driving spindle 31. The machine is now in condition for loading the next work piece 48 to be manually loaded into supporting engagement with the work supporting arbor 47.

It will be readily apparent from the foregoing disclosure that work pieces 48 are manually loaded into supporting position on the work supporting arbor 47 on each of the lapping heads 21, 21a, 21b and 21c, after which the control levers 90, 90a, 90b and 90c may be shifted to initiate a lapping cycle. After a lapping operation has been completed, the lapped work pieces are automatically ejected and the head stopped to facilitate loading a new work piece into position for the next lapping operation.

It will thus be seen that there has been provided by this invention apparatus in which the various objects hereinabove set forth together with many thoroughly practical advantages are successfully achieved. As many possible embod-

iments may be made of the above invention and as many changes might be made in the embodiment above set forth, it is to be understood that all matter hereinbefore set forth or shown in the accompanying drawings is to be interpreted as illustrative and not in a limiting sense.

We claim:

1. In a cam lapping machine having a base, a rotatable work supporting spindle to support a cam to be lapped, means to rotate said spindle, means to reciprocate said spindle axially within its bearings, a movable lapping element, means including a master cam and a follower interposed between said spindle and said lapping element to impart an oscillating movement to the lapping element during a lapping operation.
2. In a cam lapping machine having a base, a rotatable work supporting spindle to support a cam to be lapped, means to rotate said spindle, means to reciprocate said spindle axially within its bearings, a pivotally mounted lapping element, means including a master cam and a follower interposed between said spindle and said lapping element to impart an oscillating movement to the lapping element during a lapping operation.
3. In a cam lapping machine having a base, a rotatable work supporting spindle to support a cam to be lapped, means including an electric motor to rotate said spindle, means to rotate said spindle, means to reciprocate said spindle axially, a pivotally mounted lapping element, a rock shaft to support said element, a master cam on said work spindle, and a master cam follower roller cooperating with said master cam to oscillate said rock shaft during rotation of the work spindle to impart a controlled oscillating movement to the lapping element to produce the desired lapping action.
4. In a cam lapping machine having a base, a rotatable work supporting spindle rotatably to support a cam to be lapped, bearings in said base for said spindle, means including an electric motor to rotate said spindle, means including a fluid motor to reciprocate said spindle axially within its bearings, a pivotally mounted lapping element, a rock shaft to support said element, a master cam follower roller, an arm on said rock shaft to support said roller, and a master cam on said work spindle to impart a controlled oscillating movement to the follower roller and rock shaft to the lapping element.
5. In a cam lapping machine having a base, a rotatable work supporting spindle rotatably to support a cam to be lapped, a footstock which is movable to and from an operative position, means to move said footstock, a lapping element including a continuous strip of flexible abrasive paper, an indexing mechanism including a pawl and a ratchet to feed said abrasive paper, and means actuated automatically when the footstock is moved to an inoperative position automatically to advance said paper so as to present a fresh portion of abrasive paper for the next lapping operation.
6. In a cam lapping machine having a base, a rotatable work supporting spindle rotatably to support a cam to be lapped, a movable footstock, means to move said footstock to and from an operative position to facilitate a work loading operation, a lapping element including a continuous strip of flexible abrasive paper, an indexing mechanism including a pawl and a ratchet to feed said abrasive paper, and a cam actuated by said footstock automatically to actuate said pawl.

to advance said abrasive paper automatically after each lapping operation has been completed.

7. In a cam lapping machine having a base, a rotatable work supporting spindle rotatably to support a cam to be lapped, a pivotally mounted footstock, means to swing said footstock to and from an operative position, a lapping element comprising a continuous strip of flexible abrasive paper, an indexing mechanism including a pawl and ratchet to feed said abrasive paper, a cam actuated by said footstock, and a pivotally mounted lever interposed between said cam and said pawl whereby the pawl is automatically actuated when the footstock is moved to an inoperative position to index said abrasive paper so as to present a fresh portion of abrasive paper for the next lapping operation.

8. In a cam lapping machine having a base, a rotatable work supporting spindle rotatably to support a cam to be lapped, a pivotally mounted footstock, means to move said footstock to and from an operative position, a master cam on said spindle, a lapping element including a continuous strip of flexible abrasive paper, a master cam follower roller associated with said master cam and arranged to move said lapping element to impart a controlled movement to said lapping element, an indexing mechanism including a pawl and ratchet to feed said abrasive paper, and a cam actuated by said footstock automatically to advance said abrasive paper after each lapping operation so as to present a fresh portion of abrasive paper for the next lapping operation.

9. In a cam lapping machine having a base, a rotatable work supporting spindle to support a cam to be lapped, a fluid motor to reciprocate said spindle, an electric motor to rotate said spindle, a pivotally mounted footstock to support one end of a work piece, a pivotally mounted work ejector, a fluid pressure operated piston and cylinder, operative connections between said piston and said footstock and ejector, a valve to control said fluid motor, means actuated by said piston to open said valve to start the fluid motor, and electrically actuated means including a switch actuated in timed relation with said piston to start said electric motor to rotate the work piece.

10. In a cam lapping machine having a base, a rotatable work spindle to support a cam to be lapped, a fluid motor to reciprocate said spindle, an electric motor to rotate said spindle, a pivotally mounted footstock to support one end of a work piece, a pivotally mounted work ejector, a fluid pressure operated piston and cylinder, operative connections between said piston and said footstock and ejector, a stop and start valve to

control said fluid motor, means actuated by said piston to open said valve to start the fluid motor, and electrically operated means including a switch actuated by and in timed relation with movement of said piston in one direction to close a circuit to start rotation of the electric motor and spindle.

11. In a cam lapping machine having a base, a rotatable work spindle to support a cam to be lapped, a fluid motor to reciprocate said spindle, an electric motor to rotate said spindle, a pivotally mounted footstock to support one end of a cam to be lapped, a pivotally mounted work ejector, a fluid pressure operated piston and cylinder, a control valve therefor, means including a solenoid actuated latch to hold said valve in an operative position, operative connections between said piston and said footstock and ejector to actuate the footstock and ejector, a valve to control said fluid motor, means actuated by said piston to open said valve to start said fluid motor, electrically actuated means including a switch actuated in timed relation with said piston to start said electric motor, and an electric time relay which is set in motion by said switch, said relay being arranged to deenergize said solenoid after a predetermined lapping operation.

12. In a cam lapping machine having a base, a rotatable work spindle to support a cam to be lapped, a fluid motor to reciprocate said spindle, an electric motor to rotate said spindle, a pivotally mounted footstock to support one end of a cam to be lapped, a pivotally mounted work ejector, a fluid pressure operated piston and cylinder, a control valve therefor, means including a solenoid actuated latch to hold said valve in an operative position, operative connections between said piston and said footstock and ejector to actuate the footstock and ejector, a valve to control said fluid motor, means actuated by said piston to open said valve to start said fluid motor, electrically actuated means including a switch actuated in timed relation with said piston to start said electric motor, and an electric time relay which is set in motion by said switch, said relay being operatively connected to stop the work drive motor and the work rotation and to deenergize said solenoid to shift said control valve and cause the piston to move to an inoperative position, which movement closes said start and stop valve to stop the fluid motor and the reciprocation of the work spindle, swings said footstock to an inoperative position, and actuates said ejector automatically to eject a lapped work piece.

HERBERT S. INDGE.
JOHN C. BAKER.
